UNITED STATES PATENT OFFICE.

STANLEY H. LINDGREN, OF MAYWOOD, ILLINOIS, ASSIGNOR TO AMERICAN CAN COMPANY, OF NEW YORK, N. Y., A CORPORATION OF NEW JERSEY.

DREDGE CAN.

Application filed December 4, 1922. Serial No. 604,756.

My present invention relates to dredge top cans and, while it is applicable to cans adapted for a wide variety of uses, it has particular advantages in connection with containers for 5 bath and cleansing powder, and the like.

A principal object of the invention is the provision of a can of this type in which the dredging openings are normally closed and may be opened only by a positive action, 10 means being provided to automatically close the openings after the can is used.

Another object is the provision of a dredging can having the foregoing characteristics which may be readily opened by one hand by 15 the mere exertion of slight pressure upon a conveniently positioned protruding part.

The invention also has for an object the provision of simple spring means for automatically controlling the position of the closing member which may be economically provided and assembled, without adding materially to the cost of the can.

Other objects and advantages of the invention will be apparent as it is better understood from the following description, which, 25 taken in connection with the accompanying drawings, discloses a preferred embodiment thereof.

Referring to the drawings, 30 Figure 1 is a perspective view of a dredge can in which my invention is embodied;

Fig. 2 is a top plan view thereof, partly broken away and with certain of the interior parts shown in dotted lines to illustrate the 35 dredge top construction;

Fig. 3 is a section through the upper part of the can, taken longitudinally of the slide and spring; and

Fig. 4 is a section taken transversely of 40 said parts.

The can illustrated in the drawings comprises a fibre body 11, to which is secured, in any preferred manner, a sheet metal bottom end 12 and which is provided, at its upper 45 end, with a dredge top structure, to be described in detail.

An inner top member 13 is secured to the fibre body wall by means of an inner vertical wall portion 14 and a flange 15, which is 50 turned over the edge of the body wall and embedded therein, as shown at 16. Said top member is formed with a channel 17 defined by the wall portion 14, and an inner upstanding wall 18, which terminates in an elevated 55 central part 19, which, in the present instance,

is disposed slightly above the top of the body. Said raised center 19 is formed with a transverse channel 21, which serves as a guideway for a dredge slide 22. The inner top is provided with perforations at 23, disposed in 60 the channel 21, and the slide 22 has perforations 24 adapted to be brought into registration with the perforations, or openings, 23. Said slide 22 has a down-turned inner end lug or flange 25 adapted to engage the upper 65 part of the wall 18 to limit the outward sliding movement, and the outer end of said slide is turned down to provide a rounded finger-piece and stop 26.

A smooth outer top or cap 27 is secured 70 over the top 13, said outer top being held in place by a rounded flange 28 engaging the body wall beneath the flange 15. Said top 27 is cut-away to provide an opening 29, through which the slide 22 extends and it will 75 be noted that said slide is held by said top 27 in the guideway between the covers.

In order that the sifter openings may be normally closed I provide a spring 31, one end 32 of which is turned to horizontal position 80 and inserted in a groove 33 formed in the top member 13, the other end 34 of said spring being also bent to horizontal position and inserted in a retaining aperture formed in a cut-out portion 35 of the slide 22. The 85 material at the bottom of the groove 33 is slotted at 33' to permit insertion of said spring 31.

The top 27 is provided with perforations 36, corresponding to the perforations 23 and 90 24 in the inner top and slide, respectively. It will be seen that the tension of the spring 31 normally holds the slide 22 in its outer position with the end 26 protruding from the covers and, in this position the perforations 24 95 are out of alignment with those of the inner and outer covers. In order to uncover the sifter openings, it is merely necessary to exert slight pressure on the end 26 of the slide, forcing the same to its inner position with the perforations therein in alignment with those of the covers. This opening operation may, of course, be readily performed by the hand which holds the can and the slide is held in inward position while the contents are being sifted out. Upon release of said slide, the spring 31 forces it to the outward position, closing the sifter openings and, in this manner, the latter will always be closed except when the can is in use.

The parts employed in this construction are relatively simple and permit economical manufacture and the assembled container presents a plain and pleasing appearance.

- 5 The benefits of a package which will be automatically closed after use and yet is capable of being easily opened, will be manifest to those familiar with the uses to which such containers are put.
- 10 It is thought that the invention and many of its attendant advantages will be understood from the foregoing description, and it will be apparent that various changes may be made in the form, construction and arrangement of
- 15 the parts, without departing from the spirit and scope of the invention, or sacrificing all of its material advantages, the form hereinbefore described being merely a preferred embodiment thereof.

20 I claim:

1. A sifter top can, comprising a body, an undercover having an upstanding shoulder arrangeable within and against said body and having an edge turned down about the 25 end of the body into a seam, a channel arranged inwardly of said shoulder, said undercover having an upstanding central part, an outer cap of substantially flat construction having its edge curled about the turned-down 30 edge of the under cover, a slide interposed between the upwardly extending part of the under cover and arranged through the outer cap, said outer cap and slide having openings adapted to be brought into and out of 35 registration, and a spring for normally pressing the slide to move said openings out of registration, the channel and upstanding portion of the under cover holding the slide in desired contact with the under face of the 40 outer cap.

2. A dredge can, comprising a body, a top member having a flange extending over and tightly engaging the edge of said body, said top member having a peripheral channel adjacent its outer edge, providing a vertical portion engaging a substantial area on the interior of the body wall and a raised central 45 portion, a second top member positioned above said first-mentioned member, extending to and over the periphery of the can and providing a smooth outer surface, said top members having corresponding outlet openings centrally disposed therein, and a perforated movable member interposed between said top members and normally spring-held in position closing said openings and having a stop lug arranged in said peripheral channel.

3. A dredge can, comprising a body, a top 60 member having a flange extending over and tightly engaging the edge of said body, said top member having a peripheral channel adjacent its outer edge, providing a vertical portion engaging a substantial area on the interior of the body wall and a raised central

portion, a second top member positioned above said first-mentioned member, extending to and over the periphery of the can and providing a smooth outer surface, said top members having corresponding outlet 70 openings centrally disposed therein, a movable member disposed in a guideway in the inner top member and having a limiting flange extending into said channel, and spring means normally holding said movable member in closing position with the opening therein out of alignment with the openings in said top members.

4. A dredge can, comprising a body, a top member having a flange extending over and tightly engaging the edge of said body, said top member having a peripheral channel adjacent its outer edge, providing a vertical portion engaging a substantial area on the interior of the body wall and a raised central 80 portion, a second top member positioned above said first-mentioned member and providing a smooth outer surface, said top members having corresponding outlet openings 85 centrally disposed therein, a movable perforated member interposed between said top members, and a spring engaging said movable member and the fixed top part for normally holding said member in closing position with the perforations therein out of alignment with those of said outlet openings, said perforated member being movable against the tension of said spring to position exposing said openings, said fixed top part 90 having an opening through which the movable end of the spring passes to said movable member.

5. A dredge can, comprising a body, separate top members secured to an end of said body and having corresponding sifter openings therein, a slide interposed between said top members and protruding therefrom in position to be readily engaged by the thumb of the hand holding the can, said slide having a cut-out portion and being movable inwardly to arrange openings therein in registration with the openings in said top members and a spring within the body having one end engaged in said cut-out portion and its other end engaged with one of said top 105 members.

6. A dredge can, comprising a body, separate perforated members at an end of said body, and a movable closing part interposed between said members and having positions respectively opening and closing the perforations in said members, said part being normally spring-held in closing position, and a spring for so holding said part arranged within the body and passing through 110 the lower perforated member.

7. A dredging can top formed with a depressed peripheral channel and an elevated central portion extending a little above the top edge of the channel, said top having at 115

the outer side of said channel a depending flange adapted to surround and clamp the edge of the body, the central elevated portion of said top being formed with a transverse guideway, a dredging slide in said guideway, a spring for closing said slide, and a cap bearing on the top and having its marginal edge adapted to engage under the peripheral flange of the top, said top, slide and cap being perforated as described.

8. A sifter top can, comprising outer and under cap members, said outer cap member

being substantially flat and said under cap member having its central portion disposed adjacent said outer cap member, and a slide 15 arranged between said cap members and movable towards and from the periphery of the can, said under cap member having an encircling channel stiffening the same, said central portion maintaining the slide in desired contact with said outer cap member and having a transverse channel guiding said slide.

STANLEY H. LINDGREN.
